WEIGHTED SAMPLE TAB

Sydney E. Bender, New York, N. Y.

Application February 28, 1938, Serial No. 193,004

8 Claims. (Cl. 35—55)

This invention relates to weighted sample tabs, and the method of producing such weighted tabs.

The prime object of this invention is to produce a highly attractive display article in the shape of a weighted sample tab, which may be employed either individually or in conjunction with similar tabs in the form of a sample book or card, and wherein sample material of any description, but preferably fabrics of light weight, may be effectively displayed for the purpose of ascertaining their color, quality, weight, transparency, softness or other qualities discernible by touch, and which tab in addition is held normally stretched by a small weight.

Another important object of this invention is the process whereby such weighted sample tab may be efficaciously and inexpensively produced.

The foregoing and still further objects and important advantages of this invention will become more fully apparent from the ensuing description, in conjunction with the accompanying drawing, which latter however is intended to serve more or less as aid for explaining the process employed and the article produced thereby.

Referring now to the drawing,

Fig. 1 illustrates a sample card or book provided with my weighted sample tabs.

Fig. 2 illustrates a pattern, skeleton or mask as employed in the method of producing my weighted sample tab.

Fig. 3 illustrates a portion of the compressed patterns used in my process for holding sample material, ready for cutting individual tabs therefrom.

Fig. 4 illustrates a number of partially cut-out sample tabs, preparatory to applying them to the book or card.

Fig. 5 is a cross-sectional view through a portion of the preferred form of a tab, taken on lines 40 5—5 of Fig. 4.

Fig. 6 illustrates an individual sample tab of a simplified construction, and

Fig. 7 is a cross-sectional view therethrough, taken on lines 7—7 of Fig. 6.

In order to produce individual weighted sample tabs, such as shown in Figs. 1 and 4, in a practical and economical manner in what may be termed "quantity production", it is necessary to employ an expeditious method. Such method is indicated in the drawing.

I preferably produce sample tabs for light material, such as used in women's stockings, in multiple thicknesses or layers, inasmuch as the quality, transparency, as well as the color may be more readily judged in this manner. However,

for other materials single layers of samples may suffice.

Referring to the drawing, I will describe, as a typical example, the method I employ in the production of weighted sample tabs for stocking material. I prepare a plurality of patterns, skeletons or masks such as shown at 10 in Figs. 2 and 3. These patterns constitute sheets of paper or cardboard which are provided with rectangular perforations or windows 11. All perforations of 10 all patterns are intended to register when the patterns are laid upon one another.

In producing sample tabs for light stocking material, it is preferable to use a double layer of material, in which case I employ three patterns 15 i. e. two outer patterns and one inner pattern. The two outer patterns are preferably gummed at their inner faces or are provided with any other suitable adhesive, while the intermediate or inner pattern may be ungummed, but may also be provided with an adhesive at both faces, especially when the sample material is relatively thick.

One of the future outer patterns is laid flat with the gummed face upwards. Now I prepare a number of strips of stocking material of various shades and structures. I now take different strips 12, 13, 14, 15, 16, etc. and lay them over the prepared pattern in parallel, spaced relation to one another so that the strips traverse openings 11. When the entire pattern is thus covered with 30 the first layer of different sample strips, I superimpose, in registry with the lower pattern, the inner or intermediate pattern; next I apply another row of sample strips over the already placed strips so that each two overlying strips will register.

Needless to say that the materials of the overlying strips must be the same as that of strips already placed. The double sample strips are held in their flat position in any suitable manner, 40 and while thus held, the third pattern, which is the second outer pattern, is placed in registry with the already deposited patterns. Now the three layers of patterns or masks, holding in between them the stretched double strips of sample material, are forcibly compressed, preferably under the influence of heat, whereby the gummed surfaces of the patterns are caused to adhere to one another. Thus the sample strips are permanently fixed in place between the patterns.

Now the sample-holding mask is cut so that individual, weighted sample tabs are produced. This cutting operation is indicated in broken lines in Fig. 3, where a portion of the finished mask is denoted at M. For sample cards or sample books,

as illustrated in Fig. 1, it is preferable to keep the upper portions of the sample tabs together, for which reason the cut, indicated in broken lines at 17, is made throughout the length of one bar of the mask.

In order to provide the future sample tab with an individual weight and reinforcement at the bottom of the sample, it is required that the mask is cut along broken lines, indicated at 18. The article resulting from these throughcuts 17 and 18 is illustrated in Fig. 4, in which will be seen a relatively broad reinforcing bar 20 at the top edges of tabs 21, while their lower free edges are reinforced by a relatively narrow portion 22 of the mask material, which lower reinforcement serves as weight for the tabs.

It is clearly understandable that the sides of the tab material must be free, as well as the lower weighted tab edge. Thus each of the tabs when displayed in a book or on a card, such as shown in Fig. 1, may be readily observed and tested individually, and the color and texture of one tab may be conveniently compared with that of the adjoining tabs, while the tabs repose against their common background. Where however it is desirable to subject the material to touch in order to ascertain other qualities of the material, or when it is required to look through the material, the tabs are lifted and may be thus subjected to a more scrutinizing inspection. Normally, tabs lie flat or hang down, as indicated in Fig. 1. The construction shown in that figure is meant for sample cards where a great number of different shades and qualities of material is to be displayed. For individual tabs, such as illustrated in Figs. 6 and 7, the same process applies, except that bar 28 of the mask will be severed and shortened as shown at 29' in Fig. 6.

The description of the method for producing sample tabs in the manner indicated in connection with Figs. 2 and 3 calls for the employment of three layers of patterns, whereby the two layers of the sample material are spaced by the intermediate pattern, so as to facilitate the handling of each sample layer more readily. This however is not absolutely required, and it is quite feasible to employ a double layer of sample material without the spacer pattern. Such construction is illustrated in Fig. 7 where only the top and bottom patterns are utilized for producing reinforcements at the upper and lower edges.

When the material is of relatively heavy textile, only one layer is required, in which case the reinforcement may be applied either to both faces at the opposite edges of the sample or to only one face of these edges, in which event a somewhat heavier pattern material is chosen. Such construction is not shown as it is quite obvious.

On the other hand, where more than two sample layers are required for adequately displaying the material, more than one intermediate pattern may be advantageously utilized. In every event, however, it is essential that according to my invention, the sample tab must have a relatively broad reinforcement at one edge, a relatively narrow reinforcement at the opposite edge, while the lower edge and the sides of the sample tab are free, whereas the upper edge is adapted or intended for attachment to a support, such as a card or sample book, and wherein the reinforced lower edge serves as weight and stiffening and stretching means for the material.

In the foregoing description I have described
75 a specific process of my invention and specific

forms produced by my process. It is obvious, however, the sample tabs for different goods may require modified treatment in their production, leading however to the ultimate result of a weighted sample tab, for which reason it may be required in the course of manufacture to alter or improve the presently described method, and I therefore reserve for myself the right to make changes and improvements therein without departing from the broad scope of my invention, as defined in the annexed claims. 10

I claim:

1. The method of producing weighted sample tabs, which consists of preparing three sets of like patterns, skeletons or masks from reinforcing or stiffening material in the form of sheets having elongated perforations, the perforations of all patterns being adapted to register, the inner faces of the future outer patterns being provided with adhesive matter, placing parallelly a plurality of strips of sample materials over one of the outer patterns so that the strips traverse, but do not fill the elongated perforations, leaving free the longitudinal edges of the strips, placing another, inner pattern, in registry with the first pattern, over the strips of sample material, placing similar sample strips over the inner pattern, but in registry with the first laid strips, covering the now double layer of strips with the other outer pattern, compressing the now sample-filled patterns so as to cause them to adhere and so that the samples are securely held between them, and severing or cutting the now united, sample-holding patterns so as to form individual tabs of sample material, which are joined at one of their edges and free at their three other edges, and reinforced and weighted by the pattern material at their edges opposite to their joined edges.

2. The method of producing sample tabs with a stiffened and weighted edge, which comprises placing parallelly spaced strips of two layers of sample material over the gummed face of a pre-cut pattern having elongated perforations, so that the longitudinal edges of the strips remain free covering the applied strips with a correspondingly perforated, interiorly gummed pattern so that the perforations register, causing the patterns to adhere and to hold the strips, and severing the now united, strip-holding patterns into individual tabs having a relatively broad reinforcement at their upper edges, a relatively narrow reinforcement at their lower edges, and being free at their sides.

3. The method of producing weighted sample tabs, which comprises securing between two perforated, registering, interiorally adhesive patterns, parallel strips of sample material, so that the longitudinal, parallel edges of the strips remain free, and severing the now strip-holding patterns into individual tabs so that one edge of the tabs will retain a relatively broad portion of the pattern material, while the other edge will retain a narrow strip thereof. 55 60

4. The method of producing weighted sample tabs, which consists of securing to a mask, provided with elongated perforations, a plurality of parallelly disposed, spaced strips of sample material so that the strips traverse said perforations, while their longitudinal, parallel edges remain free, severing the strips and said mask into relatively short tabs so that a relatively broad portion of the mask material forms a reinforcement at one edge of the tab, and a relatively narrow portion of the mask material forms a reinforce- 75

ment and weight at the opposite edge of the tab, and both sides of the tab are free of the mask material.

5. The combination with a sample card, of a plurality of sample tabs secured with one of their ends to the upper edge of the card, the other end and the sides of the tabs being free, their lower ends having a segmental reinforcement serving as weight for the tabs, the tabs consisting of at least two layers of sample material.

10. 6. The combination with a sample card, of a sample tab consisting of a double layer of sample material, the upper edge of the sample tab being secured to the upper edge of the card, the sides and the lower edge of the tab being free, its lower edge being provided with a segmental reinforcement serving as weight for the tab.

15. 7. In a weighted sample tab for attachment to sample cards, a multiple layer of sample material in strip form, the longitudinal, parallel sides of which being free, the upper and lower ends of

the tab having exterior and interior reinforcements for holding flat and stretching the layers of sample material, the reinforcement of the upper tab end being relatively broad and oblong in form, while the reinforcement at the lower tab end is relatively narrow and segmental in shape.

8. In weighted sample tabs for attachment to sample cards, a plurality of parallelly arranged sample tab units, each unit consisting of multiple layers of sample material strips, the longitudinal, parallel sides of the strips being free, as well as their lower ends, interior and exterior reinforcements provided at the upper and lower ends of the strips, the upper end reinforcement being relatively broad and continuous and connecting the tabs, the lower tab reinforcement being individual for each tab and consisting of a relatively narrow, segmental shape, serving as weight for each tab.

10. 15. 20. SYDNEY E. BENDER.
